(57) **CLAIM**

The ornamental design for an air conditioner, as shown and described.

DESCRIPTION

FIG. 1 is the front/right-side/top perspective view of an air conditioner with closed vents showing our new design; FIG. 2 is the front-side elevational view thereof; FIG. 3 is the rear-side elevational view thereof; FIG. 4 is the left-side elevational view thereof; FIG. 5 is the right-side elevational view thereof; FIG. 6 is the top-side elevational view thereof; FIG. 7 is the bottom-side elevational view thereof; FIG. 8 shows that the vents are opened and the outlet on the top is popped up; FIG. 9 shows that the vents are opened by half; FIG. 10 and FIG. 11 show that the part(s) of the vents are working; FIG. 12 is the front/right-side/top perspective view of another embodiment of an air conditioner with closed vents showing our new design; FIG. 13 is the front-side elevational view thereof; FIG. 14 is the rear-side elevational view thereof; FIG. 15 is the left-side elevational view thereof; FIG. 16 is the right-side elevational view thereof; FIG. 17 is the top-side elevational view thereof; FIG. 18 is the bottom-side elevational view thereof; FIG. 19 shows that the vents are opened and the outlet on the top is popped up; FIG. 20 shows that the one of the vents is working; and, FIG. 21 shows that the vents are opened by half. The broken lines are for illustrative purposes only and form no part of the claimed design.
